UNITED STATES PATENT OFFICE

ALLAN GREEN, OF SUTTON, NEAR KEIGHLEY, ENGLAND

APPARATUS FOR ENCIRCLING THREADS

Application filed September 16, 1929, Serial No. 392,761, and in Great Britain September 19, 1928.

This invention relates to mechanism or apparatus whereby threads of fibrous substances are produced by a central thread being encircled or enclosed by one or more other threads that are wound around same (as for example when threads of horse hair either accompanied by other threads or alone are required to be encircled by additional threads) in order to bind or enclose the horse hair so as to prevent same from leaving the encircling threads of which they form the core. In the production of the said compounded threads it is essential that the core hairs and threads, or those which are surrounded and enclosed by the binding threads or yarns, should follow a path coincident with the axis of the circular path in which the encircling or binding threads travel when being wound around said cores. Heretofore in all cases, the compounded threads after being produced as stated have in each case continued in or to follow the said axial path until reaching a position entirely beyond the whole mass of encircling thread and the devices which carry and rotate said thread. According to my invention I mount the mass of encircling thread within a revolving member so that the axis of the said mass of thread is coincident with the axis of the revolving member. From the mass of thread thus mounted I withdraw the thread through a thread guide situated within the revolving member so that said thread is carried through same for a short space in a path lying in the axis of rotation. After passing through this central thread guide, I take said thread out of said axial path until it approaches the outer end of the revolving member carrying the mass of thread, and I then conduct said thread by appropriate guides, back to the core threads which enters the revolving member at this part. Here the encircling thread encounters and is wound around the core thread so that then this compound thread can be conducted to the outside of the revolving member for a space and forward through appropriate guiding means in order to be conducted back to the axial path beyond the mass of threads from which it is taken to be wound upon a bobbin or to form

a cop or to be otherwise dealt with as hereinafter described.

By the employment of the devices and following the method above referred to, I am enabled to form the compound thread by using single hairs or several hairs to form the core of said compound thread. Or I may use another continuous thread in addition to the hairs to produce said core.

In order that my said invention may be readily understood I have hereunto appended sheets of drawings illustrative thereof to which by figures and letters reference is made in the following description:—

Fig. 1 is an end elevation of a pair of rollers arranged to supply the selected hairs and yarns or thread which is fed to them to my improved twisting and wrapping devices shown beneath same.

Fig. 2 is a plan of the parts shown by the lower portion of Fig. 1.

Fig. 3 is a sectional plan taken on line AB of Fig. 1 and shows the formation of the devices hereinafter described.

Fig. 4 is an elevation showing a device in detail whereby the thread which has to encircle the supplied hair and threads or the hairs alone is guided in manner hereinafter explained.

Fig. 5 is a plan of the parts shown by Fig. 4.

Fig. 6 is a similar view to Fig. 4 but seen in a direction looking from right to left of said figure.

Fig. 7 is a sectional elevation of the parts shown by Figs. 4, 5 and 6.

Fig. 8 is a front elevation of the parts shown by Fig. 1.

Fig. 9 is a sectional front elevation of the upper parts of the devices shown by Fig. 8, the same being drawn to an enlarged scale.

Fig. 10 is an elevation drawn to an enlarged scale of certain of the fittings hereinafter described.

Fig. 11 is an elevation similar to Fig. 8 but shows another arrangement of devices for winding the resultant coiled or wrapped threads to form bobbins or cheeses as is well understood.

Fig. 12 is an elevation of a form of de-

tachable spindle which is used for carrying the cop or bobbin supplying the encircling thread.

Fig. 13 is an end elevation of the apparatus shown by Fig. 1 with other parts used in connection therewith and means whereby they are adjusted or held in their operating positions.

Fig. 14 is a similar view to Fig. 13 but 10 illustrates the parts in positions which they assume when the attendant disengages the retaining mechanism to permit the repairing or taking-up of broken thread as hereinafter described.

15 Figs. 9, 10 and 12 are drawn to an enlarged scale.

In carrying my invention into effect I make use of devices such as are described in the specification of my invention set forth in my concurrent application for Letters Patent in 20 the United States dated the 22nd day of April, 1929, Serial No. 357,025 which will select a single or several hairs from a bundle of hairs and will supply same so that it or 25 they may be carried forward by appropriate delivery rollers 2 and 3. These rollers are arranged to be rotated at a suitable speed in unison with that at which the supplying of the hairs thereto may require as is well known in connection with other types of machine 30 made use of in the production of threads or yarns.

In connection with the devices for selecting the hairs as above described I make use 35 of any well known devices whereby an additional thread or more than one thread may be supplied to the rollers 2 and 3 as I may desire and such supply may be from any source that will enable said thread together 40 with the hairs, to be delivered at *a* so that a thread *b* may be wound around same. The encircling movements of the said thread *b* are brought about by the cop *b*¹ which supplies same being placed within a tube 4 which 45 is of the character of a flyer and is formed to receive a spindle 5 carrying said cop *b*¹. This spindle 5 is inserted within said tube 4 and held in place by its hub 5^a resting upon a central cross-pin 4^a fixed in the lower end 50 of the tube 6.

The supply of thread *b* from the cop *b*¹ is taken endwise and vertically through the guide 4^k which is in alignment with the axis of the spindle 5, so that said thread may pass through an opening *c* formed eccentrically through the end walls 4^b of the tube 4 (see Fig. 9). The opening *c* is made through a short tube as shown by Fig. 9 so that said thread *b* may pass through said tube and (in order to effect a slight drag thereon) be wound half the way, or a little more than this, around the lower end of the funnel shaped member 4^c which is fixed upon the upper end 4^b of the tube 4. From this position the thread *b* is then taken through a

radial opening *c*¹ formed near the base of the cup shaped member 4^c in order that it may then encircle the thread *a* as the tube 4 is rotated and as the cop *b*¹ is also rotated by and with said tube 4.

The threads and hairs *a* together with the wrapping or encircling thread *b* (forming the compound thread *a*²) are then taken downwardly through the central opening in the upper end wall 4^b of the tube 4 and from 75 this position said compounded threads are carried to the outside of the tube 4 (Figs. 1 and 9) and made to pass down the outer surface of said tube 4 and forward to be delivered as is hereinafter explained.

80 The tube 4 has the lower part of its outer surface provided with ribs 4^d (which are shown to be four in number by Fig. 3 but which may be three or more than four in number) which extend upwardly along same 85 so that they will fit snugly within an outer rotary sleeve 6 while a notch made crosswise in the end of the tube 4 will span a cross pin 4^a fixed upon the sleeve 6 in order that said tube 4 with its cop *b*¹ may be rotated by 90 and when the external tube 6 is rotated.

The lower end 6^a of the tube 6 is made of 95 smaller diameter and has mounted upon it a wharle or driving pulley 7 around which takes the driving band deriving its motion from any appropriate source (as in an ordinary spinning machine) well understood, and which will transmit rotary motion to said wharle 7 in order that by said wharle 7 being secured by a nut 7^a upon the extension 6^a of the tube 6 said tube 6 may be rotated as desired.

To facilitate the rotary motions of the tube 6 and the parts which revolve with it I have 105 inner ball races *f* and *g* mounted respectively upon its lower and upper extremities while outer ball races *h* and *k* are received within bearings 8 which are pivoted at 8^a upon a suitable bracket 9 that is fixed upon framework 9^a as is shown by Figs. 13 and 14.

110 Fixed upon the hinged bearings 8 are lever arms 10 and 10^a see Figs. 13 and 14. The arm 10^a reaches vertically so that by engaging with an actuating spring *p* which is fixed upon the retaining catch 11, the attendant may arrest the motions of the parts as is hereinafter explained.

The retaining catch 11 is pivoted at 11^a 115 upon an extension from the bearing 8 in order that a handle 12, which forms the extension of the holding catch 11, may occupy a convenient position for the attendant to handle and operate said holding catch 11. The lever 10 extends horizontally to enable a rod 10^b 120 to be connected to the hair supplying devices which conduct same to the rollers 2 and 3, for the purpose hereinafter explained. Also from said lever 10, a connecting rod 13 is made 125 to reach into connection with a lever 14 piv- 130

oted at 14a upon a bracket supported by the framework of the machine 15.

This lever 14 has an extending arm 14b upon which the gripping roller 2 is mounted so that when said lever 14b is held in its position shown by Fig. 13 a spring 16 will cause the lever 14 and its arm 14b to press the roller 2 against the roller 3 and therefore grip the threads and hairs passing between it and said roller 3.

In accordance with one arrangement of the devices in connection with the lever 10 above described I make use of another connecting rod 17 which is pivoted upon the lever 10 and reaches down to enable a supporting pin 17a fixed to it to take beneath the arm 18a of a lever 18 which is pivoted upon a shaft or stud 19. Upon the arm 18 of the said lever is mounted a gripping roller 20 which is arranged to press against another roller 21 which roller 21 (in a similar manner to the roller 3 hereinbefore described) is caused to revolve at the desired surface speed to carry forward the thread a^2 which is delivered through the lower end 6a of the tube 6 as shown by Fig. 11.

When the lever 10 is raised, as is herein-after explained, to lift the lever arm 18a it causes the arm 18 to remove the gripping roller 20 from engagement with the roller 21. Whereas when the lever 10 is in its operating position as shown by Fig. 13 then the spring 22 will force the roller 20 against the roller 21 to grip the threads passing between them as desired.

When the rollers 20 and 21 are made use of I may arrange same to deliver the compounded and encircled thread a^2 down to a bobbin 23 as is shown by Fig. 11. This bobbin 23 rests upon the peripheries of two rotary drums 24 and 24a so that as these revolve in the direction indicated by the arrows w they will cause the bobbin 23 to revolve to coil upon it the yarn a^2 as said bobbin 23 revolves under well known conditions.

The guiding of the thread backward and forward over the surface of the bobbin 23 in order to effect the building of same, is carried out by a reciprocating bifurcated thread guide 25 which is operated by well known means used in ordinary thread winding machines.

When the apparatus is in operation with the handle 12 adjusted in its position shown by Fig. 13, the hook 11 is in engagement with a projection 9b formed on the rail of the framework 9a and by being thus in connection with the said projection the holding catch 11 retains the bracket 8 and all the parts it carries in their respective positions shown by Fig. 13, and in these positions the effective operations of the several parts are carried out. The rollers 2 and 3 are moved to deliver at the desired rate of speed (according to the change wheel gearing by which the roller 3

is rotated) the yarn to enable the compound thread a^2 to descend through the parts 4b down on the outside of the tube 4 forward down through the lower end of the tube 6a to be fed to the rollers 20 and 21 as before stated.

Provided one or other of the threads breaks or fails to be in continuity or provided the supply of hairs gives out or fails, then the attendant may, by pushing the handle 12 into the position shown by Fig. 14 to disengage with hook 11, cause all the parts to be brought into their respective positions shown by Fig. 14.

When the parts assume these positions the rollers 2 and 3 are separated (by the roller 2 being moved) the driving band which transmits motion to the wharle or pulley 7 is allowed to become slack and said pulley 7 is forced by the actions of gravity on the pivoted members 8 and the parts it carries, into engagement with a brake 26 which is fixed upon a bracket 26a carried by the framework of the machine.

When the motions of the pulley 7 are thus arrested the connecting rod 17 will have raised the arm 18a of the lever 18 and will also have moved the roller 20 from contact with the roller 21, thus the supply of all the threads, and the delivery of same are entirely suspended to enable the attendant to effect repairs as hereinbefore explained. To readjust the several parts in position the attendant merely operates the hand lever 12 to bring same back into its ordinary position shown by Fig. 13.

When it is desired to wind and form the compound thread a^2 on to a bobbin or spool ready for use in the shuttle of a loom I make use of another tubular member 27 as shown by Fig. 1. This tubular member forms a shield or cover for a central spindle 28 upon which a bobbin 29 is mounted. This spindle 28 is held against rotation and the bobbin taking loosely over same rests upon a disc 28a carrying a drag washer while the usual and well known vertically reciprocatory transversing motions are transmitted to the spindle 28 and its bobbin 29, to carry out the building of the coils of threads upon said bobbin 29 as is usual in machines for carrying out spinning and like operations.

Upon this sleeve 27 are mounted the driving wharle 30 which by the two pairs of anti-friction bearings 30a and 30b the wharle 30 is supported, and this wharle 30 carries extensions 31 which form a flyer by which the compounded thread a^2 is brought downward through connections w , w^1 upon the leg of the flyer 31 so that the rotations of said flyer may wind the said threads upon the bobbin 29 which is carried by the spindle 28.

In Figs. 1, 8, 9, 10 and 11 a cup shaped extension 4c is mounted at the upper end of the tube 4, but instead of said cup shaped

member I may make use of a disc $4h$ which has mounted upon it the thread guide $4k$ through which the thread b is carried and this thread b is carried through the said guide $4k$ to pass through the opening c and around the small groove $4m$ beneath the disc $4h$ so that it may pass through an opening m and therefore beneath a spring 32 as shown by Fig. 5. This spring 32 acts as a guide for the compounded threads, instead of the funnel shaped member $4c$.

When making use of the flyer 31 for winding the threads as above described, and arranging same as shown by Fig. 1, I find that on account of the false twisting or twist tube actions on the threads a which are delivered by the rollers 2 and 3 during the rotations of the flyer 31 , said twisting commences immediately the threads leave the rollers 2 and 3 and on passing downwards through the opening b^2 at the upper end $4b$ of the tube 4 and just prior to emerging from said upper end the thread b from the cop b^1 is wound around the said false twist or core threads and by running the flyer 31 at about half speed of that of the tube 4 and in the same direction, the core threads a are encircled by the threads b from the cop b^1 in the opposite direction to the false twist of said core threads a so that a complete encircling of the core threads is secured and this is desirable when the core threads which are twisted together as stated are of cotton and the encircling thread b from the cop b^1 is of silk or of artificial silk or like more costly material.

Such being the nature of my said invention what I claim is:—

1. In apparatus for producing compound threads or yarns of the character described, a flyer or rotary member for carrying a supply of encircling yarn or thread, a thread guide within said rotary member, and in axial alignment therewith, another thread guide arranged to guide the thread in a path eccentrically from the axis of the rotary member, bearings for said rotary member, another guide for conducting the same thread back to the axis of the same member, means for supplying another hair or thread to an axially situated receiving opening at the outer end of the rotary member, an opening at the side of the rotary member to permit the compound thread to be conducted to an outer part of the rotary member, another opening to permit said thread to be conducted back to an axially situated path beyond the supply of yarn or thread in the rotary member and means for transmitting motion to said rotary member.
2. In apparatus for producing compound threads or yarns of the character described, a flyer or rotary member for carrying a supply of encircling yarn or thread, a thread guide within said rotary member and in axial alignment therewith, the supply of yarn or

thread carried in the form of a cop on a bobbin, a spindle supporting said cop or bobbin, means for detachably securing said spindle within the rotary member, another thread guide arranged to guide the thread in a path eccentrically from the axis of the rotary member, bearings for said rotary member, another guide for conducting the same thread back to the axis of the same member, means for supplying another hair or thread to an axially situated receiving opening at the outer end of the rotary member, an opening at the side of the rotary member to permit the compound thread to be conducted to an outer part of the rotary member, another opening to permit said thread to be conducted back to an axially situated path beyond the supply of yarn or thread in the rotary member and means for transmitting motion to said rotary member.

3. In apparatus for producing compound threads or yarns of the character described, a detachable tubular member or flyer, a spindle detachably secured within said tubular member, means for securing said spindle within said member, a rotary sleeve for receiving the tubular member carrying the spindle, a thread guide within said rotary member and in axial alignment therewith, said member containing a supply of yarn or thread, another thread guide arranged to guide the thread in a path eccentrically from the axis of the rotary member, bearings for said rotary member, another guide for conducting the same thread back to the axis of the same member, another means for supplying hair or thread to an axially situated receiving opening at the outer end of the rotary member, an opening at the side of the rotary member to permit the compound thread to be conducted to an outer part of the rotary member, another opening to permit said thread to be conducted back to an axially situated path beyond the supply of yarns or thread in the rotary member and means for transmitting motion to said rotary member.

4. In apparatus for producing compound threads or yarns of the character described, a detachable tubular member or flyer, a funnel shaped member for guiding the threads to an axially situated opening in the end of said tubular member or flyer, a thread guide within said rotary member and in axial alignment therewith, said member containing a supply of yarn or thread, another thread guide arranged to guide the thread in a path eccentrically from the axis of the rotary member, bearings for said rotary member, another guide for conducting the same thread back to the axis of the same member, means for supplying another hair or thread to an axially situated receiving opening at the outer end of the rotary member, an opening at the side of the rotary member to permit the com-

pound thread to be conducted to an outer part of the rotary member, another opening to permit said thread to be conducted back to an axially situated path beyond the supply 5 of yarn or thread in the rotary member and means for transmitting motion to said rotary member.

5. In apparatus for producing compound threads or yarns of the character described, 10 a detachable tubular member or flyer, ribs formed radially on the outer surface of said flyer, a sleeve within which said ribs will fit snugly, a cross pin within said sleeve to take into notches formed in the end of the flyer, 15 a funnel shaped member for guiding the threads to an axially situated opening in the end of said tubular member or flyer, a thread guide within said rotary member and in axial alignment therewith, said member containing a supply of yarn or thread, another 20 thread guide arranged to guide the thread in a path eccentrically from the axis of the rotary member, bearings for said rotary member, hinged bearings for the flyer or rotary member, a retaining hook carried by said hinged bearings, an engaging piece for securing said hook, a hand lever for actuating said hook, another guide for conducting 25 the same thread back to the axis of the same member, means for supplying another hair or thread to an axially situated receiving opening at the outer end of the rotary member, means for supplying said hair or thread, 30 an opening at the side of the rotary member to permit the compound thread to be conducted to an outer part of the rotary member, another opening to permit said thread to be conducted back to an axially situated 35 path beyond the supply of yarn or thread in the rotary member, and means for transmitting motion to said rotary member.

25 6. In apparatus for producing compound threads or yarns of the character described, 30 a flyer or rotary member for carrying a supply of encircling yarn or thread, a thread guide within said rotary member and in axial alignment therewith, said member containing a supply of yarn or thread, another 35 thread guide arranged to guide the thread in a path eccentrically from the axis of the rotary member, bearings for said rotary member, hinged 40 bearings for the flyer or rotary member, a retaining hook carried by said hinged bearings, an engaging piece for securing said hook, a hand lever for actuating said hook, an arm secured to the hinged bearings supporting the flyer, pairs of rollers for supplying the core hair or thread, a rod for connecting said arm to a pivoted lever which supports one of the pairs of rollers supplying the core hair or thread, a spring for actuating the roller's supporting lever, another guide 45 for conducting the same thread back to the axis of the same member, means for supplying another hair or thread to an axially situated receiving opening at the outer end of the rotary member, an opening at the side of the rotary member to permit the compound thread to be conducted to an outer part of the rotary member, another opening to permit said 50 thread to be conducted back to an axially situated path beyond the supply of yarn or thread in the rotary member, means for transmitting motion to said rotary member, 55 another opening at the side of the rotary member to permit the compound thread to be conducted to an outer part of the rotary member, another opening to permit said thread to be conducted back to an axially situated path beyond the supply of yarn or thread in the rotary member, and means for transmitting motion to said rotary member.

60 7. In apparatus for producing compound threads or yarns of the character described, 65 a flyer or rotary member for carrying a supply of encircling yarn or thread, a thread guide within said rotary member and in axial alignment therewith, said member containing a supply of yarn or thread, another 70 thread guide arranged to guide the thread in a path eccentrically from the axis of the rotary member, bearings for said rotary member, hinged 75 bearings for the flyer or rotary member, a retaining hook carried by said hinged bearings, an engaging piece for securing said hook, a hand lever for actuating said hook, another guide for conducting 80 the same thread back to the axis of the same member, means for supplying another hair or thread to an axially situated receiving opening at the outer end of the rotary member, means for supplying said hair or thread, 85 an opening at the side of the rotary member to permit the compound thread to be conducted to an outer part of the rotary member, another opening to permit said thread to be conducted back to an axially situated 90 path beyond the supply of yarn or thread in the rotary member, and means for transmitting motion to said rotary member.

8. In apparatus for producing compound threads or yarns of the character described, 95 a flyer or rotary member for carrying a supply of encircling yarn or thread, a thread guide within said rotary member and in axial alignment therewith, said member containing a supply of yarn or thread, another 100 thread guide arranged to guide the thread in a path eccentrically from the axis of the rotary member, bearings for said rotary member, hinged 105 bearings for the flyer or rotary member, a retaining hook carried by said hinged bearings, an engaging piece for securing said hook, a hand lever for actuating said hook, an arm secured to the hinged bearings supporting the flyer, pairs of rollers for supplying the core hair or thread, a rod for connecting said arm to a pivoted lever which supports one of the pairs of rollers supplying the core hair or thread, a spring for actuating the roller's supporting lever, another guide 110 for conducting the same thread back to the axis of the same member, means for supplying another hair or thread to an axially situated receiving opening at the outer end of the rotary member, an opening at the side of the rotary member to permit the compound thread to be conducted to an outer part of the rotary member, another opening to permit said 115 thread to be conducted back to an axially situated path beyond the supply of yarn or thread in the rotary member, and means for transmitting motion to said rotary member.

9. In apparatus for producing compound threads or yarns of the character described, 120 a flyer or rotary member for carrying a supply of encircling yarn or thread, a thread guide 125 arranged to guide the thread in a path eccentrically from the axis of the rotary member, bearings for said rotary member, hinged bearings for the flyer or rotary member, a retaining hook carried by said hinged bearings, an engaging piece for securing said hook, a hand lever for actuating said hook, another guide for conducting the same thread back to the axis of the same member, means for supplying another hair or thread to an axially situated receiving opening at the outer end of the rotary member, an opening at the side of the rotary member to permit the compound thread to be conducted to an outer part of the rotary member, another opening to permit said thread to be conducted back to an axially situated path beyond the supply of yarn or thread in the rotary member, and means for transmitting motion to said rotary member.

130

within said rotary member and in axial alignment therewith, said member containing a supply of yarn or thread, another thread guide arranged to guide the thread in a path eccentrically from the axis of the rotary member, bearings for said rotary member, hinged bearings for the flyer or rotary member, a retaining hook carried by said hinged bearings, an engaging piece for securing said hook, a hand lever for actuating said hook, an arm secured to the hinged bearings supporting the flyer, pairs of rollers for supplying the core hair or thread, a rod for connecting said arm to a pivoted lever which supports one of the pairs of rollers supplying the core hair or thread, a spring for actuating the roller's supporting lever, another connecting rod pivoted to the arm extending from the hinged supports for the flyer, a spring for acting upon said rod, pairs of rollers for receiving and transferring the compound thread to the winding devices, and another lever, a projection from said rod arranged to operate said lever, said other lever arranged to support one of the pairs of rollers which receive and transfer the compound thread to the winding devices, a brake member for engaging the driving pulley when the bearings for the flyer are released, a spring for actuating said member, another guide for conducting the same thread back to the axis of the same member, means for supplying another hair or thread supplied to an axially situated receiving opening at the outer end of the rotary member, an opening at the side of the rotary member to permit the compound thread to be conducted to an outer part of the rotary member, another opening to permit said thread to be conducted back to an axially situated path beyond the supply of yarn or thread in the rotary member, and means for transmitting motion to said rotary member.
